By *Daniel Bred* ATTORNEYS.

UNITED STATES PATENT OFFICE.

GEORGE F. BEEBE, OF HORNELLSVILLE, NEW YORK.

PUMP.

SPECIFICATION forming part of Letters Patent No. 258,275, dated May 23, 1882.

Application filed April 7, 1882. (No model.)

To all whom it may concern:

Be it known that I, GEO. F. BEEBE, a citizen of the United States, residing at Hornells-ville, in the county of Steuben and State of New York, have invented certain new and useful Improvements in Pumps, of which the following is a specification, reference being had therein to the accompanying drawings.

My invention consists of certain improvements in pumps, which will be fully understood by the following description and claims.

The objects I have in view are to produce a combined lifting and force pump without stuff-ing-box or air-chamber or the use of leather or bolts, (except in connection with the han-dles and lower piston,) and small enough to be put into a bored well of four inches in di-ameter, and capable of either lifting or fore-ing water to any desired height, and not liable to injury from either frost or hot water.

In the accompanying drawings, Figure 1 is a vertical section of my improved pump. Figs. 2, 3, 4, 5, 6, and 7 are detached views.

In the construction of my pump the main cylinder or barrel A is made very long, so that the plunger B may be worked with full stroke either in the upper part or the lower. Above the spout is a second cylinder or barrel, C, with a secondary piston, D, working therein. A third cylinder or barrel, C', is made of greater diameter than the upper barrel, C, in order to allow the upper piston to play loosely therein.

The sucker-rod E is made adjustable, hav-ing a series of bolt-holes, e, therein, so that both pistons may be raised or lowered in relation to the handle F and crooked link G.

As shown in the drawings, Fig. 1, the pump-pistons are arranged to act as a force-pump, one piston acting as they go down and the other as they rise, thus giving a continuous flow of water; but when the piston-rod is lowered and the bolt H put into the upper hole e the upper piston comes down opposite or below the spout, where the chamber is enlarged and the upper piston worked loose, thus making a simple lift-pump. In case we wish to put the cylinder A lower down in the well, the two cylinders are unscrewed at b, Fig. 1, and a proper length of pipe inserted between the cylinders; and also a piece of sucker-rod, L,

is employed to lengthen the sucker-rod to equal the increased length of the water-pipe Z, Fig. 6, as is well understood by plumbers.

At the bottom of cylinder A is a check-valve, M, and the main piston or plunger B is also provided with a check-valve constructed as follows: A disk, N, is made with a large central hole, n, for sufficient supply of water, and also with bolt-holes, and the basket P has bolt-holes for the bolts R. A piece of packing, S, is placed between the disk N and basket P, and then the nuts on bolts R turned up tight, the valve O having been put in place so as to rest on the packing S when down, and thus secure a close joint and prevent wear of the metal and consequent leakage. The disk N is made of dish shape, so as to bend or mold the packing S to fit the cylinder. The upper piston, D, consists of two disks, the upper one, V, being made dishing on the lower side, and the lower disk, W, having a corresponding convex upper surface, so as to bend and mold the packing X to its proper shape.

In order to let off the water in the pump and prevent freezing, the handle is raised to its full height, when the disk N strikes the heel of the check-weight M, and thus lets off the water from the cylinder. At the same time the check-weight, by rising, strikes the stem o and opens the upper check, and thus completely empties the pump. The spout is large, and thus gives a free flow of water for ordi-nary use; but when force is required a re-ducer, Y, is employed in attaching the hose.

The packing S is known as "Jenkins' steam-packing," which is not injured by frost or hot water, and is more durable than any other pack-ing.

The cap Q and standard T may be turned to bring the handle in any position desired, and then fastened in place by a set-screw, U.

Each part may be removed and repaired in-dependently of the other parts.

Fig. 7 represents an ordinary strainer to be attached to the lower end of cylinder or barrel A, Fig. 1.

Having described my invention, what I claim is—

1. A pump provided with three working-barrels, the middle one being of greater diam-eter than the upper one, in combination with

an adjustable piston-rod and two pistons, whereby the pistons can be adjusted up or down to change the pump from a force to a lift pump and from a lift to a force pump, substantially as set forth.

2. The combination of three working-barrels with the pipe Z, for connecting the two lower barrels to adapt the pump to wells of

different depths, substantially as described and shown.

In testimony whereof I affix my signature in presence of two witnesses.

GEO. F. BEEBE.
